(57) **CLAIM**

The ornamental design for an inflator as shown and described.

DESCRIPTION

FIG. 1 is a top, front, right side perspective view of an inflator showing our design;

FIG. 2 is a left side thereof;

FIG. 3 is a right side view thereof;

FIG. 4 is a front plan view thereof;

FIG. 5 is a rear plan view thereof;

FIG. 6 is a top plan view thereof; and,

FIG. 7 is a bottom plan thereof.

The broken dash-dot lines represent boundaries of the inflator that enclose areas that form no part of the claimed design. The broken dash-dot lines represent portions of the inflator that form no part of the claimed design.
